AMPLIFYING APPARATUS

Gustav Barth, Berlin, Germany, assignor to
 Siemens Apparate und Maschinen Gesellschaft
 mit beschränkter Haftung, Berlin, Germany, a
 corporation of Germany

Application March 6, 1940, Serial No. 322,635
 In Germany December 24, 1938

12 Claims. (Cl. 179—171)

This invention relates to amplifying apparatus, and more particularly to means for amplifying an electric current.

One of the objects of the present invention is to provide novel means which are especially adapted for use in aircraft navigational apparatus for amplifying an electric current.

Another object of the invention is to provide novel means for governing a movable member, such as a control surface of an aircraft.

A further object is to provide a novel apparatus of the above character which is inexpensive to manufacture, light in weight, and which occupies a small amount of space.

An additional object is to provide novel current amplifying apparatus which can be used with direction responsive devices on board aircraft.

A further object is to provide a novel electric current amplifying device which is adapted for reversibly controlling a movable member by an output current having the same value for an input current having opposite signs.

The above and further objects and novel features will more fully appear from the detailed description when the same is read in connection with the accompanying drawings. It is to be expressly understood, however, that the drawings are for purposes of illustration only and are not intended as a definition of the limits of the invention, reference for this latter purpose being had to the appended claims.

In the drawings, wherein like reference characters refer to like parts throughout the several views,

Fig. 1 is a schematic illustration of an amplifier apparatus necessary for an explanation of the present invention;

Fig. 2 is a diagram of the characteristic curves of the device shown in Fig. 1;

Fig. 3 is a schematic illustration of another amplifier apparatus which is employed for the same purpose as the apparatus of Fig. 1;

Fig. 4 is a schematic illustration of one embodiment of the present invention;

Fig. 5 is an illustration of the characteristic curves of the embodiment of Fig. 4;

Fig. 6 is a schematic illustration of a second embodiment of the invention;

Fig. 7 is a partial schematic illustration of means, which, in combination with part of the embodiment of Fig. 6, comprise a third embodiment of the invention;

Fig. 8 is a schematic detail view of a coil cir-

cuit which can be employed with the embodiment of Fig. 6; and

Fig. 9 is another detail view of another coil circuit which can be employed with the embodiment of Fig. 6.

The forms of the invention illustrated in the accompanying drawings comprise improvements in the inventions set forth in my copending application, Serial No. 290,968, filed on August 19, 1939, and are constituted, by way of example, by improvements in means for controlling a movable member, such as a control surface of a vehicle, in accordance with a navigational instrument, such as a gyro compass, which can handle small loads only. Two amplifier units, each including a core element of magnetizable material such as "Permalloy", are herein employed which are electrically connected with one another and which have a common control member, such as a gyro compass, which governs the flow of current to an input circuit, the latter including one or more input coils upon each of said elements. An output circuit is associated with each of said units, and each of said circuits includes a plurality of output coils through which flows an alternating current. In order that only one of the above core elements be materially effective at one time, for a purpose to appear later, means are provided for giving an unsymmetrical form to the characteristic curve of each unit. The latter means comprise a rectifier in each of the output circuits and a counter-coupling coil upon each core element. The rectified alternating current in the output circuit of one element is conducted to the counter-coupling coil mounted upon the other element, and means are provided for conducting the rectified current in the remaining output circuit to the counter-coupling coil upon the remaining element.

The apparatus shown in Figs. 1 and 3 is introduced for purposes of illustrating the operating principle of the invention set forth in the above mentioned copending applications. This principle is based upon the fact that the inductance of suitable coils upon a magnetic core can be varied by controlling the permeability of the core. Suitable means are provided for controlling this permeability in accordance with a control force of a controlling instrument. In Fig. 1, a core element 10 is employed having similar members 11 and 12, which are of a highly permeable substance, such as iron-nickel alloy. The members 11 and 12 are, for example, of a rectangular or "closed" form. An input circuit is provided for element 10 having an input coil

13, which is common to members 11 and 12, and which is electrically connected to a control instrument 14, which governs, by suitable means (not shown), a flow of direct current to the coil 13. On the members 11 and 12, respectively, are output coils 15 and 16 which comprise portions of an output circuit which is energized by a source of alternating current 17. Coils 15 and 16 are in series with one another and with a rectifier 18 to which is operatively connected a suitable consuming device, such as an electric servomotor 19, the latter being operatively associated with a movable member 20. The motor 19 is preferably controllable by a rotary magnet relay device (not shown). The rectifier 18 transforms the current in the output circuit into a direct current J_1 which controls the servo-motor 19.

The magnitude of an alternating current J_2 , which flows through coils 15 and 16, is a function of the reactance of these coils. The magnitude of the direct current J_1 , which controls motor 19, is a function of the magnitude of this alternating current and is dependent upon the reactance of said coils. This reactance, in turn, is a function of the permeability of the core element 10 which corresponds to the "working point" of the magnetization characteristic curve of the device.

For reasons of simplicity and clarity, all coils shown in the drawings are assumed as being wound in the same direction. The coils 15 and 16 are connected with each other in such a manner that the voltages induced thereby in the coil 13 compensate one another.

In operation, an input direct current i_e , which flows in the coil 13, creates a constant magnetic flux in the members 11 and 12, thus displacing the "working point" of the magnetization characteristic curve. Coincident with the displacement of the "working point," there occurs a variation of the permeability and therewith a variation of the reactance of coils 15 and 16. The direct current J_1 , which controls motor 19, is consequently a function of the input current i_e .

In the diagram of Fig. 2, there is shown a characteristic curve for a device of this character which illustrates that the output current J_1 is a function of the input current i_e , the latter current being plotted against J_1 in a conventional manner. Starting from a value of the input current $i_e=0$, the output current J_1 ascends from a value of zero in approximately a straight line when i_e is positive. However, J_1 reaches a limit value when the input current has increased a predetermined amount. If the input current i_e flows in coil 13 in an opposite direction, that is, when i_e becomes negative, the same value for J_1 is obtained. Consequently, for a negative i_e a corresponding characteristic curve, as shown by the dotted line, is formed upon the opposite side of the vertical axis of the diagram of Fig. 2. Both of the characteristic curves, including the one shown by a full line and the one shown by a dotted line, are completely symmetrical with reference to the axis of ordinates. Consequently, the direction of i_e is of no importance in determining the magnitude of J_1 .

If the consuming device, which is electrically connected to rectifier 18, comprises a conventional rotary magnet, the latter can operate only in one direction because the output direct current J_1 can flow in the rotary magnet in one direction only. In other words, the direction of rotation cannot be affected. However, it is possible to reverse the direction of rotation of such

75 a magnet and hence to reversibly control the direction of rotation of a member, such as a servo-motor 19, by means of the apparatus shown in Fig. 3. The structure shown in this Figure is analogous to that appearing in Fig. 1, with the exception that a regenerator coil 21 is mounted upon the core element 10 in a manner similar to that of coil 13. Through the coil 21 there flows a direct current which is obtained from a rectifier

10 22, the latter being electrically connected to the output circuit. The effect of the direct current flowing in coil 21 is to displace the axis of the ordinates. Coil 21 thus accomplishes a pre-magnetization which, in Fig. 3, is indicated symbolically by the arrow 23. The direct current flowing in coil 21 is preferably of such a value that when i_e equals zero, the axis of the ordinates intersects the full line curve at approximately the mid-point thereof. The intersection is shown at 15 point "P" of Fig. 2. The output current corresponding to this point of intersection is J_p .

20 A rotary magnet 24 is operatively connected to rectifier 18 of Fig. 3, a coil 25 which acts upon a movable pointer, or arm 26, being electrically connected to the rectifier. As above mentioned, when $i_e=0$ the current J_p flows in the circuit connected to rectifier 18. Consequently, a torque will be continually exerted against the pointer 26. In order to maintain arm 26 in a predetermined central position, a counter torque must be exerted thereupon which, in the structure of 25 Fig. 3, is exerted by a coil 27 which is electrically connected to a suitable source of direct current for this purpose.

30 In operation, when the current i_e flows through the coil 13 in Fig. 3, a constant magnetic flux which is produced therein is indicated either by arrow 28 or 28a. This flux either intensifies or weakens the pre-magnetization which is produced by the coil 21 and thereby causes either a rise or a drop of the current J in the coil 25. Therefore, the torque which is exerted upon arm 26 of the rotary magnet reverses its direction in response to a change in direction of the 35 input current i_e .

40 The apparatus shown in Fig. 3, however, has a number of defects. For the displacement of the "zero point" of the characteristic curve there is required a permanent and a constant pre-magnetization which makes it necessary to conduct a constant direct current to the coil 21. This requires either a constant current source or as the pre-magnetization current is derived from the current source 17, as shown in Fig. 3, there must be provided means which will regulate that current source to produce a constant potential or to provide means for compensating for potential fluctuations.

45 Also, in the "zero position" of this device, that is, in a position in which arm 26 is at a predetermined central location, there flows in the amplifier system an alternating current and also the direct current J_p which corresponds to the working point "P" on the characteristic curve. This current represents a constant loss of energy.

50 An amount of energy which corresponds to the aforementioned loss must be supplied by the current source which is connected to coil 21, in order to provide the proper compensation torque or turning moment. Means (not shown) should be provided for controlling the torque exerted by coil 27 to compensate for voltage changes in current source 17 if the resultant torque in the 55 central position of arm 26 is to be zero.

The consuming apparatus 24 must therefore

be much larger and heavier than it would be if no compensating torque were required. In order to reduce the weight and power losses of devices having a single amplifier unit, such as that of Fig. 3, a double unit apparatus is provided, each unit being partially analogous to that shown in Fig. 1. The units are electrically associated in such a manner that only one thereof is materially active or effective at any one time. One unit is adapted for moving a consuming device, such as a relay, in one direction, whereas the other unit is adapted for moving the device in an opposite direction.

One embodiment of the present invention which avoids the above defects by employing a double unit amplifier is illustrated schematically in Fig. 4 in which the members 10, 10', 11, 11', 12, 12', 13, 13', 15, 15', 16 and 16' correspond to the same members shown in Fig. 1. The output circuits of both units are fed preferably from the same alternating current source 17. The direct current i_e for energizing the input circuits of units I and II is controlled by an instrument, such as a gyro compass 29. The coils 13, 13' of the input circuits are in this embodiment connected in series.

For a purpose to appear hereinafter, a counter-coupling coil 30 is mounted upon the core element of unit I in a manner analogous to input coil 13. A counter-coupling coil 30' is mounted in a similar manner upon core element II. The coils 30 and 30' are respectively energized by currents J_3 and J_4 . The former current is obtained by means of a rectifier 18' in the output circuit of unit II, and the latter current is obtained from rectifier 18 in the output circuit of unit I. Leads 31, 32 interconnect rectifier 18' and coil 30, and leads 33, 34 interconnect rectifier 18 and coil 30'.

A suitable "consumer device" is operatively connected to the apparatus comprising, for example, a relay 35 analogous to member 24 of Fig. 3. Relay 35 is provided with a movable arm 36 which is governed by opposing coils 37 and 38. The latter coils are respectively connected in the leads 34 and 32. The terminals of the apparatus to which member 35 is connected comprise terminals *a* and *d* on opposite sides of coil 37, and terminals *b* and *c* on opposite sides of coil 38. A second stage of an amplifier device can be connected to these terminals in place of member 35 in a manner to appear later. Movable arm 36 can control, for example, the direction of a current to a servo-motor (not shown) which can be operatively connected to a movable member, such as a control surface of an aircraft (also not shown).

The direction of direct currents J_3 , J_4 are determined by the direction of rectifiers 18, 18', respectively, for example, as indicated by arrows in leads 34 and 32. If the input current i_e controlled by instrument 29 flows in the direction indicated by a single arrow 39 in the leads of the input circuit, there are created by means of coils 13, 13' constant magnetic fluxes in members 10 and 10', which are indicated diagrammatically by arrows 40, 40', respectively. The currents in the counter-coupling coils 30, 30' create fluxes which are respectively indicated by arrows 41, 41'.

When the current i_e flows in the above mentioned direction, the constant fluxes resulting from the currents i_e and J_4 will add in unit I, that is, the fluxes of coils 13 and 30 will act in conjunction with one another in this unit, where-

as the fluxes of coils 13' and 30' will subtract or act in opposition to one another in unit II.

If the direction of current i_e is reversed, as indicated by arrow 42 in the input circuit, the 5 magnetic fluxes will subtract in unit I, and add in unit II. Thus, the effect of the counter-coupling coil is substantially to neutralize the electrical influence of an input coil of one unit and to intensify this influence in the other unit 10 when the input current flows in a given direction.

In operation, for a zero value of i_e certain 15 alternating currents flow in the output coils of the two units because the reactances or impedances of these coils have "final" or "limit" values. The rectified alternating current flowing in each output circuit displaces the "working point" on the magnetization curve of the opposite unit by creating a flux as above mentioned in a counter-coupling coil upon said opposite unit (Fig. 5). 20 The magnetization curve for each unit is shown in Fig. 5 under this condition, from which it is seen that corresponding to the displacement of the "working point" of each curve there exists a value of J_3 and J_4 when $i_e=0$ which is somewhat 25 larger than if the coils 30, 30' were omitted. If i_e increases in a positive direction, for example, as shown, by arrow 39 the current J_3 of unit I rises. However, in unit II when i_e increases, current J_4 drops at first to a minimum value 30 which occurs, in the present form, when the magnetic fluxes created in coils 13' and 30' compensate one another. From this point the input current i_e creates a constant magnetic flux in element 10', the strength of which is changed 35 by the effect of the increasing J_3 in coil 30'. Consequently, J_4 rises slowly with the increasing i_e .

The characteristic curve of each unit is 40 completely unsymmetrical with respect to the axis of ordinates contrary to the symmetry of the characteristic curve shown in Fig. 2. The lack of 45 symmetry creates a condition wherein for positive values of the input current i_e , starting from a zero value thereof, only the current J_3 of unit I is materially effective upon the rotary magnet 35, whereas, due to the counter-coupling of the 50 two units, the current J_4 remains below the value thereof which exists when $i_e=0$. Consequently, J_4 is substantially ineffective when $i_e=0$ and J_3 urges arm 36, for example, to the left. The opposite condition prevails when i_e is negative.

In the form shown in Fig. 4, the units I and II are similar and are constituted by the same substance. Consequently, as in Fig. 5, the characteristic curve of each unit is analogous to that of the other and the curves intersect one another at the axis of ordinates, thereby causing relay 55 35 to respond symmetrically for equal and opposite values of i_e . This is a special advantage 60 as compared with the embodiment of Fig. 3 because, as shown in Fig. 2, it is impossible to have a characteristic curve having the same form on opposite sides of the working point "P."

In order to control the slope and shape of the 65 characteristic curve of each unit, it is possible to employ an additional coil or coils in association with each of the core elements of these units. An embodiment wherein an added coil is mounted upon each element is illustrated in Fig. 6. This 70 embodiment is similar in all respects to that of Fig. 4 with the exception (1) that input coils 13, 13' are connected in parallel instead of in series, and (2) that regenerator coils 43 and 43' are respectively mounted upon core elements 10 and 10' in a manner similar to input coils 75

13 and 13'. Coil 43 is connected in lead 33 and is energized by current from rectifier 18 in the output circuit of its own unit. Coil 43' is connected in lead 31 and is analogously energized by current from rectifier 18'. In the form shown in Fig. 6, the fluxes of the regenerator coils 43, 43' support the action of the fluxes of counter-coupling coils 30, 30', respectively.

The regenerator and counter-coupling coils of Fig. 6 are in series; however, these coils can be connected in parallel as shown in Figs. 8 and 9, each of which illustrates said coils for one unit only. The circuits of Figs. 8 and 9 are similar with the exception that in the former, coil 31 is interposed between one extremity of each of coils 43 and 30', whereas in the latter coil 31 is between coil 43 and rectifier 18.

The amplifier apparatus above described in connection with Fig. 6 can be employed as an input stage of a multi-stage amplifier provided member 25 is disconnected therefrom at terminals a, b, c, d and, for example, a second amplifier stage is connected thereto. A second amplifier stage is illustrated in Fig. 7 which comprises units I' and II', the former having input coils 44, 45, the latter having input coils 46, 47. In the form shown, coils 44 and 46 are in series in a lead 49 connected at terminals a and d. Coils 45 and 47 are in series in a lead 49. The two units I' and II' are analogous to units I and II, with the exception of the input coils. Portions of units I' and II' have been omitted for clarity.

In operation, the rectified current provided by rectifier 18 flows through coils 44, 46, and the rectified current from rectifier 18' is conducted through coils 45, 47. Magnetic fluxes are created by these currents which are indicated diagrammatically in Fig. 7 by arrows 50, 51 for coils 44, 45, and by arrows 52, 53 for coils 46, 47, respectively. The arrows of the first pair are oppositely directed as are those of the second pair. When $i_e=0$ the currents in the second stage input coils are of equal values; therefore, the fluxes of coils 44, 45 compensate one another as do those of coils 46, 47. Consequently, the amplifier apparatus is in an inoperative condition. However, if a positive or negative i_e flows in the input coils of the first amplifier stage, then the fluxes directed to the right, as indicated by arrows 50, 52, or the fluxes directed to the left, as indicated by arrows 51, 53, will predominate and, for example, a relay (not shown) which is connected to the second amplifier stage, together with said second stage will become operative in a manner similar to that above described.

There is thus provided novel means for amplifying an electric current. The means are extremely light in weight, inexpensive to manufacture, and are therefore well adapted for use aboard vehicles, such as aircraft. The apparatus enables instruments such as the above mentioned compass, which can exert only a very small torque, to govern accurately the control surface of an aircraft. Moreover, the device is highly efficient in that the two amplifier units operate substantially at that point of the characteristic curve at which the energy consumption of the device is lowest when $i_e=0$. This eliminates the difficulties which are encountered in stabilizing the "working point" of the device on the characteristic curves of the device, for example, against voltage fluctuations. Also, the consuming device, such as the relay 35, requires no means for torque compensation as is necessary in the embodiment of Fig. 3. Also, by selecting the electrical qualities

of the counter-coupling coils, it is possible to correct irregularities in the device resulting from mass production, due, for example, to lack of uniformity of the magnetic qualities of the core elements.

Although only three embodiments of the present invention have been illustrated and described in detail, it is to be expressly understood that the invention is not limited thereto. Various changes in the design and arrangement of the parts can be made without departing from the spirit and scope of the invention as the same will now be understood by those skilled in the art. For a definition of the limits of the invention, reference will be had primarily to the appended claims.

What is claimed is:

1. A magnetic amplifier comprising a first magnetizable core carrying a first winding and a second winding connected in series opposed relation, a second magnetizable core carrying a first winding and a second winding in series opposed relation, a source of alternating current connected to energize the first and second windings on each of said two cores, a direct current input circuit including a third winding on said first core and a third winding on said second core, the third winding of one core being connected in aiding relation with the third winding of the other core, a fourth winding on said first core and a fourth winding on said second core, said fourth windings being wound in opposed relation, a pair of rectifiers, a first output circuit including the first and second windings of the first core, the fourth winding of the second core and one of said rectifiers, whereby the alternating current in the first and second windings of the first core is rectified and then caused to flow as a direct current in the fourth winding of the second core, a second output circuit including the first and second windings of the second core, the fourth winding of the first core and the other of said rectifiers, whereby the alternating current in the first and second windings of the second core is rectified and then caused to flow in the fourth winding of the first core, and a consuming device connected to be differentially energized by the two output circuits.

2. A magnetic amplifier comprising a first magnetizable core carrying a first winding and a second winding connected in series opposed relation, a second magnetizable core carrying a first winding and a second winding in series opposed relation, a source of alternating current connected to energize the first and second windings on each of said two cores, a direct current input circuit including a third winding on said first core and a third winding on said second core, said third windings being connected in series aiding relation, a fourth winding on said first core and a fourth winding on said second core, said fourth windings being wound in opposed relation, a pair of rectifiers, a first output circuit including the first and second windings of the first core, the fourth winding of the second core and one of said rectifiers, whereby the alternating current in the first and second windings of the first core is rectified and then caused to flow in the fourth winding of the second core, a second output circuit including the first and second windings of the second core, the fourth winding of the first core and the other of said rectifiers, whereby the alternating current in the first and second windings of the second core is rectified and then caused to flow in the fourth winding

first core, the fourth winding of the second core and one of said rectifiers, whereby the alternating current in the first and second windings of the first core is rectified and then caused to flow as a direct current in the fourth winding of the second core and in the fifth winding of the first core, a second output circuit including the first, second and fifth windings of the second core, the fourth winding of the first core and the other of said rectifiers, whereby the alternating current in the first and second windings of the second core is rectified and then caused to flow as a direct current in the fourth winding of the first core and in the fifth winding of the second core, and a consuming device having two windings one of which is connected to be energized by one output circuit and the other of which is connected to be energized by the other output circuit.

12. A magnetic amplifier comprising a first magnetizable core carrying a first winding and a second winding connected in series opposed relation, a second magnetizable core carrying a first winding and a second winding in series opposed relation, a source of alternating current connected to energize the first and second windings on each of said two cores, a direct current input circuit including a third winding on said first core and a third winding on said second core, the third winding of one core being con-

nected in parallel aiding relation with the third winding of the other core, a fourth winding on said first core and a fourth winding on said second core, said fourth windings being wound in opposed relation, a fifth winding on said first core and a fifth winding on said second core, said fifth windings being wound in opposed relation, a pair of rectifiers, a first output circuit including the first, second and fifth windings of the first core, the fourth winding of the second core and one of said rectifiers, whereby the alternating current in the first and second windings of the first core is rectified and then caused to flow as a direct current in the fourth winding of the second core and in the fifth winding of the first core, a second output circuit including the first, second and fifth windings of the second core, the fourth winding of the first core and the other of said rectifiers, whereby the alternating current in the first and second windings of the second core is rectified and then caused to flow as a direct current in the fourth winding of the first core and in the fifth winding of the second core, and a consuming device having two windings one of which is connected to be energized by one output circuit and the other of which is connected to be energized by the other output circuit.

GUSTAV BARTH.
